US00D961646S

(12) **United States Design Patent** (10) **Patent No.:** **US D961,646 S**
(45) **Date of Patent:** **** Aug. 23, 2022**

(54) **WAREHOUSE ROBOT**

(71) Applicant: **Shenzhen Hairou Innovation Technology Co., Ltd.**, Shenzhen (CN)

(72) Inventors: **Zhe Kong**, Shenzhen (CN); **Yeguang Chen**, Shenzhen (CN); **Qingxin Zhan**, Shenzhen (CN)

(73) Assignee: **HAI ROBOTICS CO., LTD.**, Shenzhen (CN)

(**) Term: **15 Years**

(21) Appl. No.: **29/777,083**

(22) Filed: **Apr. 2, 2021**

Related U.S. Application Data

(62) Division of application No. 29/701,254, filed on Aug. 9, 2019, now Pat. No. Des. 918,281.

(30) **Foreign Application Priority Data**

Mar. 13, 2019 (CN) 201930102294.2

(51) **LOC (13) Cl.** **15-99**

(52) **U.S. Cl.**

(57) **CLAIM**

The ornamental design for a warehouse robot, as shown.

DESCRIPTION

FIG. 1 is a perspective view of a warehouse robot showing a second embodiment of the claimed design;

FIG. 2 is another perspective view of the second embodiment;

FIG. 3 is a front view thereof;

FIG. 4 is a back view thereof;

FIG. 5 is a side view thereof;

FIG. 6 is another side view thereof; and,

FIG. 7 is a top view thereof.

1 Claim, 7 Drawing Sheets
